Patented Feb. 28, 1922.

UNITED STATES PATENT OFFICE.

JOSEPH M. DAPRON, OF ST. LOUIS, MISSOURI.

MEANS FOR OPERATING FARE REGISTERS.

1,408,348.

Specification of Letters Patent. Patented Feb. 28, 1922.

Application filed August 23, 1918. Serial No. 251,193.

To all whom it may concern:

Be it known that I, JOSEPH M. DAPRON, a citizen of the United States, residing in the city of St. Louis and State of Missouri, 5 have invented new and useful Improvements in Means for Operating Fare Registers, of which the following is a specification.

This invention relates to fare registers, and more particularly to means for operating the same. It has for its principal objects to produce a simple and efficient controlling and actuating means which is positive and rapid in action and operates with but slight physical effort on the part of the 10 operator; to produce a means of operation and control which does not restrict the location of the register on the car, and at the same time eliminates an extended system of operating rods, levers and other mechanical 15 elements; to produce a means of operation and control which is particularly well adapted for, but not necessarily limited to, a "one-man car," or, in other words, a car on which one person serves both as driver and fare- 20 collector or conductor; and to attain certain other advantages as will hereinafter more fully appear.

The invention consists essentially in a novel apparatus operating by fluid-pressure, 25 preferably compressed air; and, further, in the parts and combinations and arrangements of parts hereinafter described and claimed.

In the accompanying drawing illustrating 30 a practical embodiment of the invention,—

Figure 1 is a view, more or less diagrammatic, showing how an apparatus operating by compressed-air may be applied to a 40 double-acting fare register; Figure 2 is a section through the double-acting register-operating motor cylinder; Figure 3 is a section through the controlling valve cylinder; Figure 4 is a section through the check-valve cylinder; Figure 5 is an end view of a controlling valve element; Figure 6 is a similar 45 view of a modified form of the controlling valve element; Figure 7 is a section through a single-acting register-operating motor cylinder; and, Figure 8 is a view illustrating 50 a further modification wherein a fluid or liquid piston is employed.

Referring now to the drawing, the numeral 1 designates an ordinary double-acting 55 fare register, or, in other words, a register for indicating separately the number of

tickets and cash fares collected. This register is merely shown conventionally, as the particular construction of itself, except as hereinafter pointed out, does not enter into 60 the present invention.

As shown, the register 1 is provided with a reciprocator-bar or link 2, which, when moved endwise in one direction, effects the actuation of the cash indicator 3, and 65 in the opposite direction causes the actuation of the tickets indicator 4.

The actuator-bar 2 is attached, as at 5, to an arm 6 on the neck portion 7 of a double-headed piston whose heads 8 may, or may 70 not, be provided with packing rings 9, as desired. The piston works in a cylinder 10 having a slot 11 through which the arm 6 projects and is guided.

Preferably, the cylinder 10 is made in two 75 half-sections which are flanged at their meeting ends, as at 12; said flanges being apertured for the reception of securing bolts 13. So, too, the cylinder may be slotted on opposite sides, as shown more clearly in Figure 2, so as to obviate the necessity for making separate patterns; that is, the two sections are made exactly alike instead of rights and lefts as would otherwise be required. Each section is provided with the apertured 80 ears or bracket extensions 14 for the reception of screws or bolts in mounting the cylinder for use.

In use the piston is returned to neutral or normal position by the spring or springs 90 usually provided on the register; or, obviously, a spring or springs may be provided in the cylinder to act directly on the piston for this purpose.

Communicating with the ends of the cylinder 10 are pipes 15, 16, the one to supply compressed-air to actuate the piston in the direction to operate the cash indicator, and the other to actuate the piston to effect the 95 operation of the tickets indicator. 100

As shown in Figure 1, the apparatus is arranged for a double-ended car; that is, one on which the conductor's or fare-taker's station changes from one end of the car to the other at the end of the run or trip. In this 105 case, the pipes 15 and 16 respectively connect with the check-valve casings 17, 18; said casings having oppositely disposed pipe connections 19, 20 and 19^a, 20^a to the respective controlling valve casings at the ends of 110 the car or the stations occupied by the conductor or fare-taker.

According to the arrangement shown in Figure 1, there is a controlling valve, designated generally by the numeral 21, for the cash indicator actuation, and another, 22, 5 for the tickets indicator actuation, at one end of the car; while at the opposite end of the car are like valves 21^a and 22^a respectively for the same purpose.

In the respective check-valve casings or 10 cylinders 17 and 18, are piston-blocks 23 which are shifted to one end or the other of the casing according to the direction in which the fluid pressure is conducted to the casing through the pipes 19 or 20, or 19^a or 15 20^a, as the case may be; and always leaving communication open to the pipes 15, 16, but serving to effectually block off communication between the oppositely disposed pipes 19 and 20 and 19^a and 20^a.

20 The several controlling valves are alike in construction. Hence, a single description of one will suffice for all. As shown more clearly in Figure 3, this valve comprises a casing or cylinder 24 to which the conducting pipe 19, 19^a, 20 or 20^a, as the case may be, is connected at a point above a check-valve 25 which works in a chamber 26 in the lower part of the casing. Communicating with the chamber 26 is a pipe 27 leading from a suitable source of fluid pressure supply, which source may be the same usually provided for the air-brake equipment on the car. As shown, the valve 25 is yieldably held to its seat 28 by a spring 29, but it is obvious that, 30 in some cases, this spring may be eliminated and the air pressure alone depended upon to hold the valve to its seat.

Above where the pipe 19, 19^a, 20 or 20^a connects, as the case may be, the casing or 40 cylinder 24 is provided with ports or exhaust apertures 30 affording vents for a chamber 31 in which a second check-valve 32 works. This valve 32 is opposed to a seat 32^a. It may be made integral with, or attached to, 45 the valve 25, so as to work simultaneously therewith, but for convenience in the manufacture and assembling of the valve structure as a whole it is made separately, but so as to engage the valve 25 as shown in the 50 drawings.

The two valves 25, 32, are made as exact duplicates, and so as to be reversible, in order to avoid confusion in assembling them. As shown, they comprise a body portion in 55 the form of a disk (see Figures 5 and 6) whose sides are squared to afford a free passage on opposite sides when unseated, the flattening being on two or four sides, as desired. On the opposite faces of the disks 60 are stems 33 which are polygonal in cross section, whereby to afford a guide for the valve and yet permit a free passage of the air through the bores in which they work.

Resting on the stem of the upper valve 32 65 is an operating plunger or pedal-pin 34 to

be depressed by the operator, either by the application of his hand or foot, but preferably in the latter way, when it is desired to actuate the register. The pin 34 is preferably made removable so as to be taken out 70 when the operator leaves his station, and thereby prevent an accidental or unauthorized operation of the register.

For convenience in manufacture and repair, a removable plug 35 is provided in the 75 lower end of the cylinder 24, and another plug 36 is provided in the upper end, the latter having an apertured annular flange or collar 37 for attachment to the floor or platform or other convenient place in the region of the operator's station.

The check-valve 25 is normally closed and the valve 32 open (see Figure 3). When it is desired to actuate the register the operator 85 presses the plunger or pedal-pin 34, thereby seating the valve 32 on its seat 32^a and simultaneously unseating the valve 25 from its seat 28. For example, the operator presses the plunger of the controlling valve 21. The operation of the valve members 25 90 and 32 occurs as just above noted, and the air pressure is set up in the pipe 19, thereby moving the piston-block 23 to the end of the casing or cylinder 17 to check the flow into the pipe 20, which latter pipe at this time is 95 open to the atmosphere through the chamber 31 and ports 30 of the valve cylinder 21^a. The pipe 20 being thus blocked by the member 23 no pressure from the pipe 19 is set up therein, but, through the pipe 15, the compressed-air is conducted to the cylinder 10 where it acts against the piston so as to move the latter to the left, viewing it as shown in Figures 1 and 2, and thereby effecting the 100 actuation of the cash indicator 3.

Upon the release of the pressure of the operator's hand or foot, as the case may be, from the plunger 34, the valves 25 and 32 are raised by the spring 29 and air pressure from the supply pipe 27, the valve 25 seating to check communication between the pipe 27 and pipe 19 and chamber 31; and the valve 32 being unseated, the pressure in the cylinder 10 and pipes 15 and 19 is exhausted to atmospheric pressure through the ports 110 30 in the cylinder or casing 24 of the controlling valve 21; whereupon the piston in the cylinder 10 and the register-actuating mechanism connected thereto are restored to 115 neutral or normal position.

The actuation of the tickets indicator is effected in like manner by the manipulation of the controlling valve 22, the pressure being set up in the cylinder 10 through the pipes 19^a and 16, and exhausted through the ports 30 of the said controlling valve 22. The operation is the same, of course, from the opposite end of the car, but obviously through the controlling valves 21^a and 22^a, 125 and pipes 20 and 20^a.

105

130

In cases where the register is to be operated from but one end or station on the car, it is obvious that the check-valves 17 and 18 are dispensed with and the connection between the cylinder 10 and the controlling valve 21 or 22 will be as by one pipe.

It is to be understood that the stroke of the valve members 25 and 32 is relatively short; that is, just a small fraction of an inch. Therefore, the action is quick and the leakage during the movement of the valve members is almost imperceptible and there is no appreciable or undue waste of power.

By using an apparatus as herein set forth the actuation of the register is positive and effected with speed and but slight exertion on the part of the operator as compared with the usual mechanical contrivances heretofore most generally employed. It also facilitates the entire control of a car by one person, in that the controlling valve may be placed conveniently to be operated by the driver's foot, thereby leaving his hands free to control the motive equipment of the car and to attend the duties usually required of a conductor or fare-taker.

Obviously, instead of operating a double-acting fare register, as shown in Figure 1, two single-acting registers may be operated by arranging them in tandem, or otherwise, and connecting them separately to the piston extension or arm 6. So, too, a separate single-acting motor, as shown in Figure 7, may be used, in which case there must, of course, be one for each register.

It is to be understood that the term "fare register" does not confine the invention in its application to ordinary fare registers per se, but is to include fare boxes having registering mechanism such as is ordinarily operated manually or pedally by the conductor or fare-collector as the fares are deposited; and also to include fare boxes not equipped with a registering device, but having the usual trap door or valve which controls the passage of the coin or ticket from the visual receiving chamber or hopper into the final repository or compartment of the box, and which, of course, is operated at the will of the conductor or fare-collector. In this connection it is to be noted that the apparatus may be arranged to operate an ordinary fare register and a separate fare box at the same time; that is, simultaneously upon the actuation of a single controlling valve.

It is further within the contemplation of the invention to use fluid pressure other than compressed-air; and it is also obvious that the communicating end portion of the motor cylinder and the respective conducting pipes connecting the same with the controlling valves may be filled with a non-compressible fluid or liquid acting as a pliable piston against the piston in the motor

cylinder, it being understood, of course, that a piston or plunger block will be interposed between the column of fluid or liquid in the pipes 19, 19^a, 20 and 20^a and the respective controlling valves 21, 21^a, 22 and 22^a, and in which case the check-valve 17 will be dispensed with.

An arrangement for accomplishing this latter embodiment of the invention is shown in Figure 8 of the drawing. The plunger or piston block is shown as comprising an abutment or head 38 working in the larger portion 39 of a coupling cylinder 40, and a smaller head 41 working in the correspondingly smaller portion 42 of the cylinder, the two heads being connected by a neck 43. Hence, when the fluid pressure from the controlling valve is brought to bear on the head 38, the head 41 is pressed against the column of fluid or liquid in the pipe 19, which in turn actuates the piston in the motor cylinder 10; the supply and release of the pressure being controlled through the valve 21 as hereinbefore described.

It is also obvious that the apparatus admits of considerable further modification and alteration without in the least departing from the spirit of the invention as defined by the appended claims, and, therefore, it is not limited to the specific construction shown in the drawing.

What is claimed is:

1. In an apparatus of the character described, a register, a fluid pressure motor having an operable connection with said register whereby to actuate the latter, and a controlling device, normally maintained by the fluid pressure supply for exhausting the pressure from said motor and being operable at the will of the operator for checking the exhaust and simultaneously admitting the fluid pressure to said motor.

2. In an apparatus of the character described, a register having a spring-restored actuator mechanism, a reciprocating piston motor, the piston of said motor having means thereon for actuating the actuator mechanism of the register when the piston is moved in one direction and means whereby the piston is restored to normal position after such actuation, a conducting pipe for fluid pressure to said motor, and a controlling device having means yieldably maintained by the fluid pressure supply for normally exhausting pressure in said conducting pipe and being operable at the will of the operator for checking the exhaust and at the same time admitting the fluid pressure to said conducting pipe.

3. The combination of a fare register, a fluid pressure motor having an operable connection with the actuator mechanism of the register, a conducting pipe for fluid pressure connected to the motor to operate the same, and a controlling device having means

- for exhausting pressure in said conducting pipe, co-operating check elements respectively controlling the exhaust from and the pressure supply to said conducting pipe, 5 said check elements having a correlated and co-operative inverse actuation whereby the one is closed when the other is open, and being maintained normally by the fluid pressure supply to exhaust the pressure in said 10 conducting pipe and simultaneously check pressure supply thereto and means operable by the operator at his will for effecting the actuation of said check elements from normal position.
- 15 4. In an apparatus of the character described, a reciprocating piston motor, controlling devices located respectively at two opposite stations, conducting pipes connected at their outer ends to said controlling devices, respectively, and at their meeting ends to a branch coupling, a branch conducting pipe connected at one end to said coupling and at its opposite end to said motor, and a reciprocating check element in said coupling, said check element being operable by the pressure in either of said first mentioned conducting pipes and serving to prevent communication between the same, but permitting communication between said branch 25 30 35 conducting pipe and the one of said first mentioned conducting pipe in which pressure is induced, the said controlling devices having means for normally exhausting pressure in the respective conducting pipes and means for checking the exhaust and at the same time admitting pressure to the respective conducting pipes at the will of the operator.
5. The combination of a double-acting fare register, a double-acting reciprocating piston motor, the piston of said motor having means for actuating the actuator mechanism of the register when the piston is moved in either direction, and controlling devices, operable at the will of the operator, for effecting the actuation of said motor.
6. In an apparatus of the character described, a conducting pipe, a supply pipe, and a controlling device connecting said pipes communicably, said device having an exhaust outlet, a check-valve controlling communication between said conducting pipe and said exhaust outlet and being normally open, a check-valve controlling communication between said conducting pipe and said supply pipe, and being normally closed by the pressure in the supply pipe and an operating element operable at the will of the operator for closing said first mentioned check-valve and at the same time opening said second mentioned check-valve.

Signed at St. Louis, Missouri, this 5th day of August, 1918.

JOSEPH M. DAPRON.
